[57] CLAIM

The ornamental design for a page printer, as shown and described.

DESCRIPTION

FIG. 1 is a perspective view taken from the top, front and left side of a page printer showing my new design;

FIG. 2 is a front elevational thereof;

FIG. 3 is a right side elevational thereof;

FIG. 4 is a left side elevational thereof;

FIG. 5 is a rear elevational thereof;

FIG. 6 is a top plan view thereof;

FIG. 7 is a bottom plan view thereof; and

FIG. 8 is another perspective view thereof with the paper tray removed.

The broken line representation of a paper tray in FIGS. 1, 3, 4, 6, and 7 are for purposes of illustration and form no part of the claimed design.
